CONDENSATION VACUUM PUMP

Frank Edmund Bancroft, Sale, and Charles Walter Miller, Roundhay, Leeds, England, assignors, by mesne assignments, to General Electric Company, a corporation of New York

Application January 11, 1940, Serial No. 313,390
In Great Britain January 12, 1939

3 Claims. (Cl. 230—101)

This invention relates to condensation or diffusion vacuum pumps of the kind designed and constructed for operation with an organic liquid, for example the oil which is known as "Apiezon" oil ("Apiezon" being a registered trade-mark) or other organic liquid having a vapour pressure considerably lower than that of mercury. The invention furthermore is essentially concerned with pumps of the kind which have a plurality of outwardly directed jets in tandem or series in each tubular pump body or casing. An example of such a pump is described in the specification of British Letters Patent No. 407,593. In this example there are virtually a plurality of pumps in parallel in a single casing, each pump comprising a single vapour uptake tube having two jet cowls in tandem and co-operating with its own tubular portion of a multiple condenser structure. Another example of such a pump is described in the specification of British Letters Patent No. 477,013, this pump being a form of self-fractionating pump wherein the series of cowls appertain to respective uptake tubes.

An object of the present invention is to improve the efficiency of pumps of the kind above specified.

Considering the design of such a multistage oil diffusion pump it is now known that a low backing pressure is in general associated with a high speed jet, and also that the jet nearest the fore-vacuum has usually, in consequence of its high backing pressure, a low speed.

It is also known that in vertical pumps of the kind specified the clearance between the bore of the pump, that is the condensing surface, and any of the lower cowls of the jets of the pump must not be made less than a critical dimension since if the clearance is too small the condensate from any higher jet in the pump will bridge the gap and thus prevent satisfactory operation of the pump. In practice, it is necessary to effect a compromise as between the avoidance of the aforesaid bridging of the gap by the condensate, and in the interests of obtaining the small clearance which is requisite for the desired high backing pressure.

It has been found that another aspect of an efficient pump of the kind specified is that the speed of any particular jet should be sufficiently high to maintain a fine side pressure which is lower than the critical backing pressure of the jet immediately above it, regardless of what may be the backing pressure of the aforesaid particular jet, provided this backing pressure is less than the critical value for that particular jet. Fur-

thermore, it is necessary that this condition should be satisfied for all values of "throughput" for which the pump is designed and constructed. This means, in effect, that assuming the pump has a jet A with a backing jet B these jets having respectively speeds S_A and S_B and the critical backing pressure of the jet A is P_A and if P_M is the maximum fine side pressure at which the pump is required to operate, then S_B must be greater than

$$\frac{P_M \cdot S_A}{P_A}$$

consequently maximum use is made of the high critical backing pressure of the lowermost jet since the latter is the first to fail when the backing pressure is allowed to increase. This latter consideration of speed also affects the clearance which must be chosen between the cowl and the inner wall of the pump body or condenser surface. Since, however, increase of speed is usually accompanied by decrease of backing pressure it will be uneconomical to arrange that the lowermost jet has a higher speed than that which fulfills the conditions indicated above, after allowing a sufficient factor of safety.

In diffusion pumps of the kind specified, as have actually been constructed and used by the present applicants and other workers in the art, the pump bodies have been of uniform bore and the lower speed and higher backing pressure of the lower jets has been obtained by employing lower cowls of larger diameter whereby to decrease the clearance between said cowls and the pump bore.

In pumps constructed for high speed, which pumps in virtue of their relatively higher speeds have bodies with relatively larger diameter bores than is the case with pumps designed and constructed for lower speeds, it will be appreciated that for the same gap between cowl edge and bore the annular jet space and therefore the speed of the jet for a given minimum gap will be larger than is actually necessary in respect of the lower jets, and consequently the critical backing pressure of such pumps is low.

There is a still further aspect which has been found to be desirable to take into account in the design of such pumps. Considering, by way of example, an element of jet clearance space of fixed width and length, the length being large compared with the width as is usual in practice, such an element might be expected to have a fixed pumping speed since its area is fixed. If, however, such an element is bent along an arc of

a circle, there is for any given radius of arc, a maximum free path for a molecule in the space in the plane of the arc. Now it can be seen that the smaller the radius of the arc, the smaller is this maximum free path. The existence of long free paths introduces the possibility of collisions between vapour molecules such as may cause some of the molecules to reach the high vacuum or fine side of the jet so that back streaming may be set up giving rise to back diffusion. This back diffusion besides having the well known effect of lowering the speed of the jet, interferes with the mass downward movement of the vapour to cause a lowering of the critical backing pressure of the jet.

It will thus be clear that, from consideration of the above effect only, it is desirable to keep the radius of the annular gap small in a jet designed for relatively high backing pressure.

According to the present invention which is 20 based upon the considerations set forth above, in a vertical pump of the kind specified the cowls of some or all of the jets other than the uppermost jet are substantially not of greater diameter than that of the uppermost cowl and conveniently these cowls have approximately the same diameter as that of the uppermost cowl, whilst in addition the bore of the pump casing or surrounding tubular condenser surface is made less, preferably progressively, where it co-operates with the lowermost and any intermediate jets, than is the case with the uppermost jet of the pump. Such reduction in diameter can be effected in various ways of which several are hereinafter exemplified.

After considerable experiment and adjustments of the various parts and operating conditions it has been found that better results are obtained with a pump according to the invention above set forth, if the several jets are fed from respective uptake tubes instead of from a single common uptake tube and a possible reason for this is that since with a single uptake tube the amount of vapour being fed from any one jet is dependent to some extent on the vapour being fed from another jet and since the several jets feed into such relatively widely different fore-vacua, variation of vapour distribution occurs when the final backing pressure, that is that of the lowermost jet is allowed to increase.

Therefore, according to a subsidiary feature of the invention the several jets of the pump are fed from respective uptake tubes or they might be fed from separate boilers although the latter alternative is obviously less practicable. It is desirable, however, that the jets should act as though fed from separate boilers. Multi-jet pumps having separate uptake tubes have, of course, already been proposed, originally, possibly in British Specification No. 251,213 describing a multistage mercury vapour pump.

It is not necessary that the several uptake tubes should be carried to the bottom of the common boiler although obviously they must be carried below the oil level, or below the respective oil levels which obtain during the operation of the pump.

According to a still further subsidiary feature of the invention the diameters of those parts of the uptake tubes which extend into the boiler are varied so as to adjust the effective boiler area which feeds each jet since in general it has been found desirable for good results that the boiler area feeding the lower jets should be greater than that feeding the higher jets. As 75

the result of experiments, one particular pump which has been constructed having two stages and which had good characteristics, the ratio of the boiler area feeding the lower jet was twice that feeding the upper jet.

In carrying out the main feature of the invention the pump bore or condenser surface may be made conical so that the gaps between the several jets and the condenser surface are graduated in the manner hereinbefore indicated, the several cowls of the jets being conveniently of substantially the same diameter and associated with respective uptake tubes which at their lower ends are flared or expanded and extend into 10 the boiler, which latter is of wider diameter than that of the smallest internal part of the pump casing.

In another arrangement the condenser surface or pump bore may comprise a plurality of cylindrical portions of graded diameter and merging the one into the other by short conical portions which may be located above the respective associated jets.

In a further alternative arrangement of carrying out the invention a pump substantially as illustrated in the specification of British Patent No. 346,293 may be modified in the following ways. Firstly, a second cowl of annular form is secured around the uptake tube 2 shown and described in the aforesaid earlier specification, this additional cowl being preferably of cylindrical shape. The external cylindrical diameter of this cowl is preferably substantially the same as the maximum diameter of the uppermost cowl 6. Within the confines of 25 this second cowl the uptake tube 2 is provided all around it with a plurality of perforations and above these is a ring which is externally secured to the inside of the uptake tube 2 of the aforesaid earlier specification, and internally has 30 secured to it the upper end of a second uptake tube which also has an expanded lower end dipping into the boiler. With this arrangement 35 it will be appreciated that for the additional jet, vapour from the boiler travels in the annular space between the original and the additional or inner uptake tubes and emerges from the aforesaid perforations.

Secondly, the main feature of the present invention is completed in this arrangement by the provision within the uniform bore of the condenser or pump body, of a tubular member or liner which, as will be appreciated, effects the desired reduction of the pump bore for co-operation 40 with the lower cowl to form the jet of the relative dimensions hereinbefore set forth. Said liner should either be itself cooled by the circulation of a cooling fluid therein for which purpose it should be channelled or made hollow, or 45 as has been found, it can be maintained sufficiently cool if its external cylindrical surface is made a good push fit within the bore of the pump body or condenser surface that is to say if care is taken that a good thermal contact is made between these members.

The upper and lower ends of the liner tube are preferably flared from the interior. Preferably also the upper and lower ends of the liner are externally reduced slightly in diameter so as to provide oil traps which effectively prevent air from being sucked up between the liner and the pump bore.

It will be understood that a still further jet might be added by making the bore of the aforesaid liner member stepped or conical and such

an arrangement is of general application for the purpose of the invention.

The original pump before modification as aforesaid, has a speed of 20 litres per second and a backing pressure of about 80μ , when operating with what is sold as "Apiezon" B oil as the working fluid and operating with 600 watts in the heater. After modification, under the same conditions, the backing pressure was increased about $3\frac{1}{2}$ times. It will be appreciated that still higher backing pressures may be obtained with the use of "Apiezon" A oil although in this case the ultimate vacuum obtainable with the pump will not be quite so good.

According to still another subsidiary feature of the invention the pump may be arranged to fractionate in the manner which is per se well known and has been described by various workers in technical publications, whilst as a convenient example of a pump adapted to fractionate the specification of British Patent No. 475,062 may be referred to. To this end the uptake tubes may be brought down close to the surface of the boilers; preferably they are brought into contact therewith and provided with a few holes in relatively staggered arrangement so as to ensure that the oil travelling radially inwards from the rim of the boiler cannot pass through any section thereof to another section further inwards without having to travel along a considerable and tortuous path, thus occupying an appreciable amount of time in doing so.

In the accompanying drawing—

Figure 1 is a diagrammatic sectional elevation illustrating a diffusion pump in accordance with the invention. On the left-hand side the condenser surface is shown as being conical whilst on the right-hand side is shown an equivalent arrangement wherein the condenser surface is stepped.

Figure 2 is a sectional elevation showing how the pump substantially as illustrated in the drawing of the specification of British Patent No. 346,293 can be modified according to the present invention.

Figure 3 is a sectional elevation of the boiler and the lower parts of the uptake tubes of a self-fractionating pump according to the present invention.

Referring first to Figure 1 of the accompanying drawing, at 1 is shown the boiler, at 2, 3 and 4 consecutive jets fed respectively by the uptake tubes 5, 6 and 7 by vapour from the boiler 1 of the diffusion pump. At 8 and 8a is shown the condenser surface which is provided with a cooling jacket 9. The jets 2, 3 and 4 are provided in a manner per se well known with the respective cowls 10, 11 and 12 at the respective upper ends of the uptake tubes 5, 6 and 7. The lower ends of these uptake tubes are flared as clearly shown and the boiler is of greater diameter than that of the part 13 of the pump casing. It will be seen that, as hereinbefore set forth, the diameters of the two lower cowls 11 and 12 are approximately the same as that of the uppermost cowl 10 and are cylindrical, whilst the bore of the condenser surface 8 or 8a progressively decreases downwards.

Referring to Fig. 2 of the accompanying drawing, reference should be made to the drawing

accompanying the specification of British Letters Patent No. 346,293 aforesaid. Comparing Fig. 2 of the present application it will be seen that the pump shown in the said earlier specification is modified substantially only by additions as follows. Firstly, a second cowl 14 of annular form is secured by an internal flange to the existing uptake tube 15 and the latter is provided with two rows of holes 16. Within the uptake tube 15 is a ring 17 secured to a second uptake tube 18 which is also flared at 19 and extends into the boiler 20. Within the uniform bore 21 of the condenser is the tubular member or liner 22. Conveniently the member 22 is secured by screws 23 engaging the uptake tube 15 but the member 22 is a good fit within the bore 21 so as to have good thermal contact therewith. As shown, the upper and lower ends of the member 22 are flared at 24. Also the upper and lower ends of said member 22 are reduced in diameter so as to provide the channels 25. It will be appreciated from an inspection of the accompanying Fig. 2 that the diameter of the lower cowl 14 is substantially the same as the diameter of the upper cowl 26 which is supported on the central rod 27 of high thermal conductivity material, from the floor of the boiler 20. It will be seen that the lower ends of the uptake tubes are brought down to the floor of the boiler 20 and are provided with perforations 28 and 29 whereby the pump may be self-fractionating. In this respect it will be appreciated that as indicated the level of the oil in the three annular compartments is different during operation.

Referring lastly to Fig. 3 of the accompanying drawing, which shows only a boiler and three uptake tubes for a three-jet pump, the tubes are represented at 30, 31 and 32, whilst the boiler is indicated at 33. The tubes are flared and brought down to the floor of the boiler whilst holes 34, 35 and 36, few in number and in relatively staggered arrangement are provided, and the diameters of the lowermost ends of the uptake tubes are arranged to give different boiler areas substantially as hereinbefore set forth.

We claim:

1. A vertical diffusion pump of the type which includes a plurality of superimposed cowled jets discharging downwardly into a condensing space defined by the wall of the pumping chamber, wherein the cowls associated with the various jets are of substantially uniform diameter and the wall of the pumping chamber is of progressively reduced diameter in a downward direction for the purpose and with the effect of decreasing the clearances between the lower cowls and the said wall.

2. A diffusion pump according to claim 1 in which the lower cowls are of cylindrical contour and uniform diameter, while the pump wall is of downwardly tapered character.

3. A diffusion pump according to claim 1 in which the reduction of the diameter of the pumping chamber at the region of the lower cowl is accomplished by the insertion of a tubular liner having a smaller bore than the pumping chamber as a whole.

FRANK EDMUND BANCROFT.
CHARLES WALTER MILLER.
